ROBERT REIMANN AND ABSALOM PERCIVAL PARSELLE, OF BIRMINGHAM, ENGLAND.

MANUFACTURE OF SEAMLESS TUBES.

1,213,539.

Specification of Letters Patent.

Patented Jan. 23, 1917.

Application filed April 13, 1914. Serial No. 831,376.

To all whom it may concern:

Be it known that we, ROBERT REIMANN and ABSALOM PERCIVAL PARSELLE, both subjects of the King of Great Britain, and residing, respectively, at 288 Slade road, Birmingham, and 71 Minstead road, Gravelly Hill, Birmingham, Warwickshire, England, have invented certain new and useful Improvements in the Manufacture of Seamless 10 Tubes, of which the following is a specification.

This invention relates to the manufacture of seamless tubes, particularly metal tubes, of the kind in which a pierced billet or bloom is mounted upon a mandrel which is fed between a pair of pilger rolls.

For the most part the invention relates to improvements on machines of the type described in our and others' prior British Patent specification No. 25667 A. D. 1912.

In the accompanying drawings, which illustrate the preferred method of carrying out this invention, Figure 1 is a longitudinal section showing the machine used for feeding the billet up to the pilger rolls, and rotating it during the feed. Fig. 2 is a similar sectional view of an addition to that machine. Fig. 3 is a section on the line 3—3 of Fig. 2 looking toward the left. Fig. 4 is a section on the line IV—IV of Fig. 1.

Like letters indicate like parts throughout the drawings.

In the type of machine to which this invention applies a pair of rotating pilger rolls is used of some well known type, and a heated billet is fed up to these rolls and is forced into the gap of the rolls. Subsequent rotation of the rolls throws out the billet, and at each rotation of the roll the billet is forced back and again fed up to the rolls. During this forward movement it is rotated slightly and fed farther forward.

In the machine described in the prior British patent referred to the feed bar or spindle to which the mandrel was attached had formed upon it a "spiral" which engaged a stationary overrunning clutch so arranged that as the feed bar moved in one

direction the spiral overran but was prevented from rotating, whereas when it moved in the opposite direction the spiral caused rotation of the feed bar. The feed bar is relatively heavy and possesses considerable momentum with the result that it is apt to overrun causing erratic operation, and it is the object of the present invention to enable a better finished tube to be obtained by overcoming this and another objection. It is necessary to surround the mandrel with a tubular guide or support, and this interferes with the finishing of the end of the bloom, which is overcome in the present case by automatically withdrawing this support.

To obtain improved feed the spiral is, in the present machine, mounted upon a short light shaft geared to the feed bar, and as the shaft carrying the spiral possesses little momentum accurate operation results.

In the present construction the feed bar A instead of carrying a spiral spline or keyway is formed with a straight spline B or the equivalent, and it slides through a gear 75 wheel C with which it is rotatively connected by means of the spline. The wheel C gears with another wheel D fixed to a short shaft E which is supported in suitable bearings in the brackets E². This 80 shaft E carries spiral splines or threads, and attached to the reciprocating ram F, through which the bar A passes quite freely, is a bracket G carrying a ratchet device at H the inner member of which engages the splines. This ratchet device is of any suitable type. For instance, it may comprise a nut H engaging the spiral splines on the shaft E, while the periphery of the nut is formed with ratchet teeth engaged by a pawl H' carried by the bracket G.

The ram F is attached to a piston E² which works in the cylinder F³ to which compressed air or the equivalent can be admitted by means of a supply tube F⁴. A 95 vent is provided at F⁵ to allow the piston to move freely to the left. A stuffing box is provided at each end of the cylinder. The ram F carries at its forward end a screwed spindle H³ which can be operated by means 100

of the hand wheel illustrated, and the spindle at its lower end carries a half-nut H^2 which engages a screw thread A^2 on the feed bar. It will be understood that when the nut H^2 is in engagement with the thread on the feed bar reciprocation of the piston causes similar movement of the feed bar. Also, that if at each stroke of these parts in one direction the feed bar is rotated slightly 10 it will, owing to the nut and thread connection between the bar and the ram cause the bar to screw farther to the left, or move a greater distance than the ram. This is effected as follows:—As the ram moves to 15 the right due to the throw-out action of the pilger rolls the ratchet device at H overruns and no rotation is imparted to the feed bar. When compressed air is admitted by the tube F^4 to the cylinder the parts move to the left and the ratchet device at 20 H is held by the pawl and the spiral E is caused to rotate. This rotation is transmitted through the gears D C to the feed bar. As stated, rotation of the feed bar 25 causes it also to project farther from the ram. Thus when the ram has completed its forward stroke the billet is pushed farther into or through the rolls.

The bloom Y is attached to a mandrel Z 30 as usual, (see Fig. 2) but instead of this being fixed directly to a socket X on the feed bar A , an intermediate bar J is used, which is screw-threaded at J^2 , and which threads are slotted, as indicated at J^8 , to form a key- 35 way. The usual sleeve or support K is attached to a nut L , which screws on the thread J^2 , and the nut L carries a plunger N which is arranged to be held in the keyway formed in the threads by means of a spring. 40 When the plunger is seated in the keyway J^3 , the nut and sleeve K rotate with the bar J . If, however, the plunger is withdrawn and the nut held stationary, the nut will screw back over the screw-threaded bar J 45 and the sleeve K will be withdrawn. The plunger, therefore, has attached to it a trigger M , which is caused to engage a curved stop O , carried by the standards P of the machine. Normally the sleeve K supports 50 the mandrel, as shown in Fig. 2, until the trigger M strikes the stop O . The trigger then moves and withdraws the plunger and also holds the nut stationary while the bar is longitudinally moved relative to the nut 55 by the operation which is being performed on the billet. With the usual constructions, the support K advances with the mandrel, and as it must extend as close to the billet Y as is possible, it prevents the billet being 60 finished off to the extreme end by the rolls. By arresting this advance in this way, the billet can be finished to the end, effecting economy.

It will be seen that by the spiral being 65 mounted upon the comparatively light shaft

E it possesses little momentum so that inaccuracy due to excessive rotation of the feed bar is prevented.

What we claim as our invention and desire to secure by Letters Patent is:—

1. In a machine for use with a pilger mill, the combination of a reciprocating feed bar, a ram for moving the feed bar, means for reciprocating said ram, a screw and nut connection between the feed bar and the ram, a shaft carried by the ram having a spiral thread, means for preventing the rotation of the shaft when moving in one direction, a gear wheel slidably mounted on the shaft and arranged to rotate therewith, a second gear meshing therewith and slidably mounted on the feed bar and arranged to rotate therewith, and means for restraining the gears from movement in a longitudinal direction with the feed bar and shaft, substantially as set forth.

2. In a machine for use with a pilger mill, the combination of a reciprocating feed bar, a ram for moving the feed bar, means for reciprocating said ram, a screw and nut connection between the feed bar and the ram, a shaft connected to the ram and arranged to be reciprocated therewith, a spiral thread on said shaft, a pawl and ratchet connection between the ram and the shaft carried by the ram and arranged to retain the shaft from rotation when the ram is moved in one direction, a gear wheel on the shaft and adapted to rotate therewith, a second gear wheel on the feed bar and adapted to rotate therewith, and bearings for said gear wheels, said bearings being adapted to maintain the gear wheels from movement in a longitudinal direction with the shaft and the feed bar, substantially as set forth.

3. In a machine for use with a pilger mill, the combination of a reciprocating feed bar, a ram for moving the feed bar, means for reciprocating said ram, a screw and nut connection between the bar and the ram, supporting brackets mounted on the ram, a gear wheel mounted in said brackets surrounding the feed bar, a spline connection between the feed bar and said gear wheel, a shaft mounted on the ram and adapted to move therewith, a spiral spline on said shaft, a second gear wheel mounted on the shaft and the spiral spline seated between said brackets, and means for preventing the spiral shaft from rotating when the ram is moved in one direction, substantially as set forth.

4. In a machine for use with a pilger mill, the combination of a feed bar, a ram, means for reciprocating said ram, a screw and nut connection between said feed bar and said ram, a shaft geared with said feed bar, a spiral on said shaft, and a ratchet device carried by said ram, causing said shaft to rotate during reciprocation of said ram in

one direction only, a screwed bar carried by said feed bar, a mandrel attached to said screwed bar, a guide for said mandrel, a nut carried by said guide, and engaging said 5 screwed bar, and a stop device engaged by said nut causing it to disengage from said screwed bar substantially as set forth.

In testimony whereof we have signed our

names to this specification in the presence of two subscribing witnesses.

ROBERT REIMANN,
ABDALOM PERCIVAL PARSELLE.
